United States Patent Office

Des. 180,245
Patented May 7, 1957

180,245

AUTOMOBILE

John M. Reinhart, Birmingham, Mich., assignor to Ford
Motor Company, Dearborn, Mich., a corporation of
Delaware

Application August 10, 1954, Serial No. 31,807

Term of patent 3½ years

(Cl. D14—3)

FIG. 1

FIG. 4

FIG. 2

FIG. 3

Figure 1 is a side elevational view of an automobile showing my new design, partly broken away to expose the interior portion thereof;

Figure 2 is partly an end view of the door and partly a fragmentary section of the lower frame to illustrate the interior contour in enlarged detail;

Figure 3 is a fragmentary detailed view of the lower door and panel member; and

Figure 4 is an enlarged view of the interior portion shown in Figure 1.

The side of the vehicle broken away or not shown is a mirror image of the opposite side disclosed.

The dominant feature of my design resides in the full line portion of the drawings.

I claim:

The ornamental design for an automobile, as shown and described.
